Patented Oct. 19, 1915.

FIG. 3

Lewis H. Holcomb

By *Shigley & Harvey* Attorneys

UNITED STATES PATENT OFFICE.

LEWIS H. HOLCOMB, OF COLUMBUS, OHIO.

VALVE-LIFTER.

1,157,223.

Specification of Letters Patent.

Patented Oct. 19, 1915.

Application filed April 22, 1915. Serial No. 23,058.

To all whom it may concern:

Be it known that I, LEWIS H. HOLCOMB, a citizen of the United States of America, residing at Columbus, in the county of 5 Franklin and State of Ohio, have invented certain new and useful Improvements in Valve-Lifters, of which the following is a specification.

The present invention relates to improvements in valve lifters for use in connection with internal combustion engines for the purpose of lifting the valves from their seats in order to gain access to certain parts of the engine, for replacing valves, etc without the necessity of long, tedious work and resort to laborious proceedings and handling of the cylinder or motor as is frequently the case.

The primary object of the invention is 20 the provision of a tool that may be handled with facility, by one person, that is compact and durable, efficient, and capable of adjustment so that it may be used in places, ordinarily difficult of access, with facility.

25 The invention consists in certain novel combination and arrangements of parts as will be fully described and claimed and as illustrated in the accompanying drawings.

I have depicted one complete example of 30 the physical embodiment of my invention constructed according to the best mode I have so far devised for the practical application of the principles of my invention, and while I have illustrated and shall describe 35 the device as a valve lifter, it will of course be understood that I shall avail myself of all the uses to which the implement may be subjected, and that the device may be altered within the scope of my claims.

40 Figure 1 is a side elevation of a device made according to my invention. Fig. 2 is a top plan view of the device of Fig. 1, showing in dotted lines the capability of adjustment of the device. Fig. 3 is a plan view of a different sized jaw by which the implement may be adapted for use with different sized valve stems etc. Fig. 4 is an edge view of the jaw of Fig. 3, showing in dotted lines the fixed jaw of the tool. Fig. 5 45 illustrates the use of the implement (shown in dotted lines) as applied to an exhaust valve of an internal combustion engine, the spring of the valve being shown as compressed.

50 In the preferred embodiment of the invention as illustrated in the drawings I

have shown two parallel jaws 1 and 2, the former a movable or slidable one and the latter stationary, or fixed with relation to the jaw 1. The movable jaw 65 is slidable on the post 3 which is rigid with and fixed to the jaw 2, and the post is grooved at 4 for accommodation of the feather 5 carried by the sleeve 6 of the jaw 1. In this manner the jaw 1 through the 65 medium of its sleeve 6 is movable or slidable on the post, but lateral movement of the jaw with relation to the post is prevented by the engagement of the feather of the jaw in the groove of the post. By this arrangement and combination of parts it will be 70 seen that the movable jaw is capable of a direct and straight motion with relation to the fixed jaw so that, when compressing the valve spring 7 the spring is moved in a direct line and is held against deviation. This is a most desirable feature of the invention as it prevents the accidental displacement of the spring when the latter is unsupported.

80 The jaw 1 is moved through the medium of a pair of lever handles 8 and 9, the former pivoted at 10 in a fulcrum link 11 and pivotally connected at 12 to a bolt 13 swiveled in a bracket arm 14 integral with 85 and projected from the sleeve of the movable jaw.

85 The two handles or levers 8 and 9 are made preferably from stamped metal, the sections of each handle being joined together by rivets as 15 while the operating ends of the handles are forked or spread apart to accommodate the link 11 and their swivel bolts. The link 11 as clearly seen is a metallic strip fashioned with a series of 90 fulcrum holes 16 to receive the pivot pin 10, and at 17 the link is pivoted in the lever handle 9. The lever handle 9 is in turn pivoted at 18 to the bolt 19 which is swiveled in the bracket arm 20 directly in line with 95 and beneath the swivel bolt 13 of the lever 8. A lug 21 is provided on the handle 9 to retain the handle 8 when the jaws are held open. Both the jaws have mouths or cut away portions as 22, and in Fig. 2 the mouth 100 or cut away portion is of a size to span or fit around a large size valve stem 23, but to adapt the implement to smaller size stem, I employ detachable supplemental jaws 24 as 105 illustrated in Figs. 3 and 4. The mouth 110 of such a jaw is made of smaller dimensions, and the supplemental jaw is formed with

side flanges 26 and central lugs 27 so that the supplemental jaw may be slipped over the jaws 1 or 2 and secured by a set bolt 28 to the first jaw. In this manner the jaws 5 are adapted to the variable diameters of valve stems, and they may be detachably held by the bolt 28 passed through the opening 29 in the jaw 24.

In Fig. 2 the radius of movement of the 10 jaws upon their swiveled supports is indicated by the dotted circular line, and it will be seen that the jaws may be bodily and synchronously turned upon their swivel supports throughout a wide radius thus enabling 15 the device to be used with facility in other wise inaccessible and difficult places.

By means of the series of openings 16 in the link 11 the fulcrum point of the lever 8 may be altered and the movement of the 20 slidable jaw with relation to the fixed jaw may be adjusted to adapt the device for use with different sized valve accessories.

In using the device, the two jaws are in closed position, in contact, with the two handles spread apart. The fulcrum bolt 10 of course has been properly adjusted to the required height, and the swiveled jaws have been swung around to the proper angle in order to get at the valve stem and spring in 30 proper position. The lever handles are now brought together by swinging the handle 8 on its pivot or fulcrum bolt 10 and this action raises the movable jaw 1 so that it slides upwardly on its post while the jaw 2 re-

mains stationary resting upon the fixed portion 30 of the valve device. As the movable jaw is raised it lifts the loose collar 31 of the stem and thus compresses the spring 7 so that access may be had to the cotter pin 32 (dotted lines Fig. 5) or other attention 40 given to the valve device as required. The lever arms are held in position by crossing one over the other and permitting the end of lever 9 to rest between the lugs 21 and the lever 8 to which it is fixed. In this manner 45 the spring is held compressed and the hands are free to perform the work required.

What I claim is:—

1. A device as described comprising a pair of pivotally joined lever handles, a pair of 50 jaws one of which has a straight line movement relative to the other, and a swivel joint between each jaw and its handle permitting the jaws to swing at right angles to the plane of the handles.

2. A post a jaw fixed thereon and a jaw 55 slidable on the post, a pair of lever handles pivoted to the jaws and pivoted together, and a swivel joint between the handles and jaws.

3. A post a jaw fixed thereon and a parallel jaw slidable on the post, a pair of lever handles pivoted to the jaws, and an adjustable pivotal link connecting said handles, and a swivel joint between each handle and 60 its jaw.

In testimony whereof I affix my signature.
LEWIS H. HOLCOMB.
